UNITED STATES PATENT OFFICE.

JOHANN ERNST BERNSTEIN, OF DRESDEN, GERMANY, ASSIGNOR TO THE FIRM
ZÜNDFIDIEUSPATENTVERWERTUNGSGESELLSCHAFT M. B. H., OF BERLIN,
GERMANY.

MATCH.

Application filed April 19, 1921. Serial No. 462,763.

To all whom it may concern:

Be it known that I, JOHANN ERNST BERNSTEIN, a citizen of the German Republic, residing at Dresden, Germany, have invented 5 certain new and useful Improvements in Matches, of which the following is a specification.

This invention relates to matches particularly those having a stem made from paper. 10 In order to facilitate the ignition of such match, when the same is being lighted a paper strip is arranged at the side of the head. When the match is being lighted this paper strip catches fire and conducts the fire 15 to the stem of the match. The paper strip—called the igniting beard—can be added to the paper match as a separate part or, which is simpler, the igniting beard can be made in one piece with the paper match which is 20 simply slit at the end of the head so that the priming head with the priming composition is situated at the one side of the gap formed by the incision, the igniting beard being situated at the other side of said gap. The 25 ignition beard is thus as close as possible to the priming cap whereby a certain ignition is secured. The manufacturing is very simple as only an incision is required for producing the igniting beard.

According to this invention the paper strip is saturated or coated with inflammable or combustible material such as paraffine or the like behind the priming head and behind the igniting beard so that a small interval exists between the inflammable material and the priming cap whereby the ignition is facilitated as the part free from paraffine or the like is easily ignited by the priming cup and by the igniting beard. 40 The paraffine or other combustible used, burns before the stem, the stem acting as a sort of a wick, and thus the flame lasts for a longer period than if the match were not coated.

In order that the invention may be clearly understood I shall proceed to describe the same with reference to the two forms of construction shown by way of example by the accompanying drawing wherein:

Fig. 1 shows a paper match of one form of construction and

Fig. 2 a paper match of the other form of construction.

The match *a* of paper as shown by Figures 1 and 2 has a paper strip *c* at the side of the priming head *b*. This paper strip *c* serves as igniting beard. In the two forms of construction shown by way of example the strip *c* is made in one piece with the stem. As shown by Fig. 2 the igniting beard *c* is 55 separated from the priming head *b* merely by an incision. At some distance behind, so that an interval is formed, a strip *d* of paraffine or the like is provided. This strip *d* is produced by coating or saturating with 60 paraffine this part of the paper match *a*. The incision separates the end of the match 65 a into two approximately equal parts. This presents the advantage that when the matches are connected at the lower ends in a strip and the strip is folded so that the matches are placed upon one another an igniting beard *c* is always placed upon a priming head *b*, two priming heads never 70 being placed the one upon the other. Any 75 danger of self-ignition by the rubbing together of the priming heads is thus prevented. Furthermore the packet of folded up match-strips is quite thin and compact.

The matches are preferably made in a 80 comb or strip of paper of the usual form and the strip is preferably folded as above set forth or cut to suitable lengths.

I claim:

1. A match having a priming head and an 85 igniting beard at one end, the igniting beard being separated from the priming head by an incision and being disposed adjacent the priming head.

2. A match having a priming head and an 90 igniting beard at one end, the igniting beard being separated from the priming head by an incision and being disposed adjacent the priming head, and a band of combustible material on the match at a distance from 95 the priming head and igniting beard.

In testimony whereof I affix my signature in presence of two witnesses.

JOHANN ERNST BERNSTEIN.
